(57) **CLAIM**

The ornamental design for a lamp lens, as shown and described.

DESCRIPTION

FIG. 1 is a perspective view of a lamp lens showing embodiment 1 of my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear side perspective view thereof;

FIG. 9 is a front side perspective view thereof, shown the state of use;

FIG. 10 is a perspective view of a lamp lens showing embodiment 2 of my new design;

FIG. 11 is a front elevation view thereof;

FIG. 12 is a rear elevation view thereof;

FIG. 13 is a left side elevation view thereof;

FIG. 14 is a right side elevation view thereof;

FIG. 15 is a top plan view thereof;

FIG. 16 is a bottom plan view thereof;

FIG. 17 is a rear side perspective view thereof; and,

FIG. 18 is a front side perspective view thereof, shown the state of use.

The broken lines in the drawings depict portions of the lamp lens that form no part of the claimed design.
